UNITED STATES PATENT OFFICE.

SOULIADA CODERRE, OF HOLYOKE, MASSACHUSETTS.

CLEANER FOR ROLLS.

No. 901,783.

Specification of Letters Patent. Patented Oct. 20, 1908.

Application filed March 30, 1908. Serial No. 424,095.

To all whom it may concern:

Be it known that I, SOULIADA CODERRE, a citizen of the United States of America, residing at Holyoke, in the county of Hampden and State of Massachusetts, have invented a new and useful Cleaner for Rolls, of which the following is a specification.

My invention relates to improvements in devices designed especially for cleaning and polishing drier rolls which form a part of paper-making machinery, and consists generally of a pair of peculiarly constructed shoes which are adapted first to be positioned in contact with the rolls to be cleaned and polished, and then to be actuated with a reciprocating movement longitudinally of such rolls until the latter, which are revolving meanwhile, have had their peripheries restored to the desired condition, as herein-after set forth.

Metallic rolls used as conveyers and especially the drier rolls of a paper machine are liable to rust and to become coated with sizing and other substances from the paper which passes over them, so that it is necessary from time to time to remove such foreign matter in order to prevent injury to the paper, and the object of my invention is to provide simple and inexpensive but efficient means for doing this work.

A further object is to produce a cleaner that can be readily attached to and detached from the frame which supports the rolls to be dressed, and to provide simple means for this purpose, it being understood, of course, that when attached to said frame the device is in operative position relative to said rolls.

I attain these objects by the means illustrated in the accompanying drawings; in 40 which—

Figure 1 is a side elevation of my cleaner showing it applied to a pair of rolls, portions only of said rolls and the supporting frame therefor appearing; Fig. 2, a left-hand view of the cleaner alone as it appears in Fig. 1, and, Fig. 3, a plan view of the bottom shoe, as shown in Fig. 1, the upper portions of its fixed and movable arms being broken off.

50 Similar figures refer to similar parts throughout the several views.

Referring to the drawings it will be observed that this device comprises two shoes 1

having concave faces adapted when covered in the manner described below to be pressed 55 against the peripheries of the rolls, an arm 2 rising from the lower shoe, an arm 3 extending downward from the upper shoe, connecting means for such arms, and a rocker-arm 4 pivoted at 5 to a lug 6 on said lower shoe. 60 In addition to the aforesaid members there are four spring clips 7 attached at their centers by rivets 8 to what may be termed the backs of the shoes 1 adjacent to the longitudinal edges thereof and having their ends 65 connected by cross-pieces 40, a bolt 9 which passes through a hole 10 in the arm 3 and a longitudinal slot 11 in the arm 2, a washer 41 and a nut 12 on said bolt, and a spring 13 having one end fastened to said arm 3 and 70 the other end to a lug 14 on top of the arm 4. The concave faces of the shoes 1 are covered first with some yielding material, as leather, and then with pieces of sand-paper 15. The leather pieces, represented at 16, are permanently affixed to the shoes in any suitable manner, but the sand-paper 15 is held in place by the clips 7 the cross-pieces 40 of which are closed on the folded edges of said sand-paper, as best shown in Fig. 1, with 80 sufficient force to prevent displacement of these pieces during the cleaning operation. When the pieces 15 are worn out, their release is effected by freeing them from the clips 7, and then new pieces are placed on 85 said shoes, bent over the ends of the latter, and inserted between said clips or their cross-pieces and said shoes, as before. The clip cross-pieces 40 are provided with handles 17 which may be grasped for the purpose of facilitating the act of drawing said cross-pieces away from the shoes when it is desired to release the ends of the sand-paper or to engage such ends. A supporting rod 18 and an actuating rod 19 are also associated with the device, and there is an opening in the head 20 of the arm 4 to receive the first-mentioned rod, and a perforated lug 21 on the arm 2 to receive the second-mentioned rod, which latter is fastened to said lug by nuts 22—22 on 90 the rod both sides of the lug.

In Fig. 1 I show fragmentary parts of two drier rolls 23 and of a frame 24 which supports them, the frame having a vertical slot 25 therein, and to this slotted portion of the 105 frame on the inside an arm or bracket 26 is

secured by means of a plate 27 on the outside of the frame and a bolt 28 and nut 29. The bracket 26 is horizontally slotted at 30 for the bolt 28, which slot and the frame slot 25 permit said bracket to be properly located for the support of one end of the rod 18 which is received in a fork 31 at the free end of the bracket and there secured against lateral displacement by a removable pin 32.

10 On the opposite side of the frame is a similar bracket similarly supported for the rod 8, except that this second bracket need have only an ordinary opening for the end of said rod which is carried by said bracket. A collar 33 is fastened on the rod 18 by a set-screw 34 adjacent to each bracket 26 to hold the rod against endwise movement.

The above described supporting means for the rod 18 will vary in different machines, 20 therefore I do not intend to restrict myself in this matter by limiting my invention to any particular means of support for said rod.

Assuming that the faces of the shoes 1 are properly covered in the manner explained, 25 the device is made ready for use by mounting it in position and adjusting said shoes to the rolls 23 in the following manner: First the arm 4 is mounted on the rod 18 and said rod is secured to its supports with the lower shoe 30 resting on the lower roll, and then the nut 12 is loosened, the arm 3 is raised to bring the upper shoe against the upper roll, the slot 11 for the bolt 9 permitting this to be done, and said bolt is again tightened. If at the start, 35 however, the shoes are too far apart to enter beneath the rolls, the nut 12 must be loosened and the shoes brought closer together before an attempt is made to place the device in operative position. After the shoes have 40 been thus brought into contact with the rolls the tendency of the spring 13 is to force said shoes hard against said rolls and to so retain them owing to the peculiar construction of the parts and the position of said spring.

45 If the rod 19 has not already been attached to the lug 21, it is attached now, and the operation of cleaning and polishing the rolls is proceeded with, while said rolls are in motion, by grasping said rod and actuating the 50 device to and fro the entire length of the rolls until they are free from foreign matter and thoroughly scoured, the arm 4 mean- while riding on the rod 18.

With the present supports for the rod 18 55 said rod is usually left in the machine, therefore, in order to mount the arm 4 on the rod, it is necessary to remove the pin 32 and the associated collar 33, swing the rod out of the fork 31, slide the head 20 on to the rod, re- 60 place the latter in said fork, and return said collar to position on the rod where it is once more secured by means of its set-screw 34, the rod bearings in the closed bracket and said head 20 being sufficiently loose to per-

mit the rod to be swung out of the fork and 65 then to receive said head. At the end of the cleaning operation the device is removed from the machine and from the rod in practically the same way that it was placed in operative position.

I may modify my cleaner more or less for the purpose of adapting it to different styles of rolls and for this reason do not wish to be restricted to the exact construction herein shown and described.

70 What I claim as my invention, and desire to secure by Letters Patent, is—

1. The combination, in a roll cleaner, of two shoes, means of connection between such shoes, an arm directly connected with one of said shoes and adapted to be mounted to slide on a rod, and a connecting member between the free end of said arm and said means of connection between the shoes.

75 2. The combination, in a roll cleaner, of two shoes, arms connecting such shoes, an arm connected with one of said shoes and adapted to be mounted to slide on a rod, and a spring extending between said last-mentioned arm and the adjacent shoe arm.

90 3. The combination, in a roll cleaner, of two shoes, longitudinally adjustable arms connecting such shoes, an arm connected with one of said shoes and adapted to be mounted to slide on a rod, and a spring extending between said last-mentioned arm and the adjacent shoe arm.

95 4. The combination, in a roll cleaner, of two shoes provided with connecting arms, continuous spring clips centrally fastened to such shoes, cross-pieces connecting the ends of such clips, said clips and cross-pieces being arranged and adapted to grasp the ends of covers on the faces of the shoes, an arm connected with one of said shoes and adapted to be mounted to slide on a rod, and a spring extending between said last-mentioned arm and the adjacent shoe arm.

100 5. The combination, in a roll cleaner, with a suitably supported rod, of an arm provided with a head which is capable of being slidably mounted on said rod, two shoes provided with connecting arms, one of such shoes being provided with a lug to which said first-mentioned arm is pivoted, and a spring extending between said head and the adjacent shoe arm.

105 6. The combination, in a roll cleaner, with a suitably supported rod, and an actuating rod, of an arm provided with a head which is capable of being slidably mounted on said first-mentioned rod, two shoes provided with connecting arms, one of such shoes being provided with a lug to which said first-mentioned arm is pivoted, a spring extending between said head and the adjacent shoe arm, and means to attach said actuating rod to one of the shoe arms.

7. The combination, in a roll cleaner, with a supporting rod, and releasable means for supporting said rod and securing it against endwise movement, of a rocker-arm provided with a head which is capable of being slidably mounted on such rod, two shoes having said rocker-arm pivoted thereto, and a spring extending between the rocker-arm and the adjacent shoe arm.
